UNITED STATES PATENT OFFICE.

VINCENT DE PASCAL, OF MARSEILLE, FRANCE.

DESIGN FOR A RING FOR A SHOE HEEL OR SIMILAR ARTICLE.

Application filed January 11, 1928. Serial No. 24,807. Term of patent 7 years.

To all whom it may concern:

Be it known that I, VINCENT DE PASCAL, citizen of the French Republic, and a resident of Marseille, in the Republic of France, have invented a new, original, and ornamental Design for a Ring for a Shoe Heel or Similar Article, of which the following is a specification, reference being had to the ac-

companying drawing, forming part thereof.

The figure is a perspective view of a ring for a shoe heel or similar article showing my new design.

I claim:

The ornamental design for a ring for a shoe heel or similar article, as shown.

VINCENT DE PASCAL.
